UNITED STATES PATENT OFFICE.

DAVID A. EBINGER, OF COLUMBUS, OHIO, ASSIGNOR TO THE COLUMBUS HEATING AND VENTILATING COMPANY, OF COLUMBUS, OHIO, A CORPORATION OF OHIO.

CLOSET-SEAT.

No. 911,220.

Specification of Letters Patent.

Patented Feb. 2, 1909.

Application filed October 11, 1907. Serial No. 396,877.

To all whom it may concern:

Be it known that I, DAVID A. EBINGER, citizen of the United States, residing at Columbus, in the county of Franklin and State 5 of Ohio, have invented certain new and useful Improvements in Closet-Seats, of which the following is a specification.

My invention relates to closet seats and has for its object the provision of a device of 10 this character constructed in such manner that it will be effectually protected against moisture and will be strengthened and braced against cracking and warping.

Further objects and advantages of the 15 invention will be set forth in the detailed description which now follows.

In the accompanying drawing: Figure 1 is a transverse vertical section through a closet having this improved closet seat mounted 20 thereon, Fig. 2 is a plan view of said seat with certain of the parts broken away, and, Fig. 3 is a detail perspective view looking at the underside of the closet seat.

Like numerals designate corresponding 25 parts in all of the figures of the drawing.

Referring to the drawing the numeral 5 designates the closet bowl. Strips 6 rest upon the edge members of the bowl and have openings 7 formed therein. The closet seat 8 30 is preferably made of wood and a metallic plate 9 which conforms to the shape of the seat and which has an opening 10 formed therethrough which conforms in shape and registers with the opening 11 of the seat, is 35 secured to the underside of said seat by screws 12. Lugs 13 formed upon this plate are adapted to enter the openings 7 of the strips 6 to hold the closet seat in position.

Since the strips 6 rest upon the edges 14 40 of the bowl, it follows that the edges 14 lie slightly below the upper faces of the strips and open spaces would therefore exist between the undersides of the metallic plate 9 and the upper faces of the edges 14 of the 45 bowl. To close this space to thereby prevent the passage of fumes from the bowl therethrough, ribs 15 are formed upon the underside of the plate, said ribs being preferably cast integral with the plate. When the closet seat

is placed in position, these ribs rest upon the 50 upper faces of the bowl edges 14 and not only aid in supporting the seat, but close said spaces.

I am aware of the fact that wooden closet seats have been provided, braced with metal 55 to prevent the said seats from warping and cracking when subjected to moisture. So far as I am aware, however, all efforts in this direction have been directed toward merely bracing the seat and I am not aware of the fact 60 that a metallic plate which conforms to the shape of the closet seat and which completely covers the underside of said closet seat to protect the seat against moisture, has ever been employed. This plate not only 65 protects the seat against moisture, but so braces and strengthens it in every direction, as to effectually prevent any tendency of the seat to warp or crack.

I therefore claim:

1. The combination with a latrine closet 70 of a seat adapted to rest loosely thereon said seat comprising a wooden body portion and a metallic plate conforming to the shape of said body portion and entirely covering the 75 bottom of the seat said plate having a pair of integral ribs cast thereon, said ribs lying between upstanding portions of the latrine closet to prevent endwise movement of the seat.

2. The combination with a latrine closet 80 of a seat adapted to rest loosely thereon, said seat comprising a wooden body portion and a metallic plate conforming to the shape of said body portion and entirely covering 85 the bottom of the seat said plate having a pair of integral ribs cast thereon, said ribs lying between upstanding portions of the latrine closet to prevent endwise movement of the seat, and tenons also integral with 90 said plates, said tenons entering recesses formed in said upstanding portions.

In testimony whereof I affix my signature in presence of two witnesses.

DAVID A. EBINGER.
